[57] CLAIM

The ornamental design for a power supply support frame, as shown and described.

DESCRIPTION

FIG. 1 is a perspective view of a power supply support frame showing my new design;

FIG. 2 is an elevational view of one side thereof, the other side being a mirror image;

FIG. 3 is a top plan view thereof; and

FIG. 4 is an elevational view of one end thereof, the other end being a mirror image.

FIG. 1.

FIG. 2.

FIG. 3.

FIG. 4.
